UNITED STATES PATENT OFFICE

169,474

SCARF

Lucien Deroubaix, Paris, France, assignor to Edgar C. Hyman Co. Inc., New York, N. Y., a corporation of New York

Application January 21, 1953, Serial No. 23,204

Term of patent 7 years

(Cl. D92—1)

To all whom it may concern:

Be it known that I, Lucien Deroubaix, a citizen of the Republic of France and a resident of Paris, France, have invented a new, original, and ornamental Design for a Scarf, of which the following is a specification, reference being had to the accompanying drawing, forming a part hereof.

Figure 1 is a view showing the left half section of the scarf, the dotted lines representing the mid-point thereof, and

I claim:

The ornamental design for a scarf, substantially as shown and described.

LUCIEN DEROUBAIX.
